DOORLOCK

Application filed October 7, 1924. Serial No. 742,198.

This invention relates to door locks, and particularly to improvements on the structure shown in my copending application entitled "Door locks," filed August 8, 1923, 5 Serial No. 656,335.

The object of the present invention is to generally improve and simplify the construction and operation of locks of the character described; to provide a lock embodying an inner and an outer knob, with means for locking the outer knob against rotation, said means comprising a button-actuated mechanism carried by the inner knob; and further, to provide a lock of this character 15 in which the outer knob may be released by turning movement of the inner knob in one instance, and by a key-actuated mechanism in another instance.

One form which my invention may assume is exemplified in the following description and illustrated in the accompanying drawings, in which—

Fig. 1 is a central longitudinal section of the lock.

Fig. 2 is a similar section, taken at right angles thereto or on line 2—2 of Fig. 5.

Fig. 3 is a cross-section on line 3—3 of Fig. 2.

Fig. 4 is a cross-section on line 4—4 of Fig. 1.

Fig. 5 is a cross-section on line 5—5 of Fig. 1.

Referring to the drawings in detail, and particularly to Fig. 1, A indicates in general a lock housing which is cylindrical in cross-section and which encloses a latch-actuating mechanism. B indicates a housing which is also cylindrical in cross-section and which carries a latch C and an actuating mechanism. The portion of the lock indicated at A will hereinafter be referred to as the latch-actuating mechanism, and the portion of the lock carried by the housing B will be known as the latching mechanism.

The latch-actuating unit, besides supporting and housing the latch-actuating mechanism, also forms a support for a pair of spindles D and E. Each spindle is provided with a knob, one knob being indicated 50 at 2 and the other at 3. The knob 2 will

hereinafter be referred to as the outer knob and the knob 3 as the inner knob. The inner knob is centrally perforated as indicated at 4 and it forms a support for a push button 5. This push button actuates a mechanism hereinafter to be described, which locks the spindle D and the knob 2 against rotation. The knob 2 is also centrally perforated as indicated at 6 and it carries a key-actuated mechanism generally indicated at 7, which serves the function of releasing the knob 2 and the spindle D when locked. Other means are employed for releasing the spindle D and the knob 2 when locked. This mechanism is actuated by turning movement of the knob 3 and the spindle E, and it will also be later referred to. In fact the invention involved in the present instance involves the following features; a lock having an inner and an outer knob; means for locking the outer knob against rotation; means actuated by turning movement of the inner knob for releasing the outer knob, and a key-actuated mechanism operable independent thereof and also serving the function of releasing the outer knob.

The means for locking the spindle D and the outer knob against rotation embodies the push button 5 and the mechanism actuated thereby. This push button is carried by the inner knob. The key-actuated mechanism which releases the outer knob 2 is mounted in the outer knob, and the means actuated by turning movement of the inner knob for releasing the outer knob is carried within the latch-actuating housing A. All of these features will be described in detail, but before proceeding with this description, a further description will be given of the lock in general.

The spindles D and E are journaled in bearing extensions 8 formed on an escutcheon plate 9 secured on each side of the door generally indicated at F. The spindles project to a central point within the lock housing A. A slight spacing is, however, left between the spindles as indicated at 10, so that there is no danger of interlocking, and furthermore, to permit free actuation of each spindle independent of the other. Both

5 spindles are split or have key-ways formed therein as indicated at 11, the key-ways being provided for two purposes, first, that of locking the knobs against rotation about the spindles, and secondly, that of locking one of the spindles and knobs against rotation, to-wit, the outer spindle and knob indicated at 2.

10 The spindles are secured against endwise movement to prevent them from being pulled out of the lock, but as this feature is covered in my copending application, and in other pending applications, it is thought unnecessary to give a detailed description 15 thereof.

Both spindles serve a common main function, to-wit, that of retracting the latch indicated at C. This is accomplished as follows: Mounted within the main housing A 20 is a cup-shaped plate 12. Secured thereto in any suitable manner is a retractor guide 13, and slidably mounted within the guide and guided thereby is a retractor carriage 14. The inner end of each spindle terminates in a pair of shoulders such as indicated at 16 and 16a (see Fig. 5). These shoulders engage the end of the retractor carriage and limit its movement in one direction; in fact the retractor carriage is held in engagement 25 with these shoulders by means of a spring 17. Turning movement of either spindle through means of the knobs forces one shoulder 16 or another into engagement with the end of the retractor carriage, and it is 30 thus moved in the direction of arrow a. (See Fig. 5.)

The outer end of the carriage is provided with a pair of hook-shaped members 18. These hook-shaped members interlock with 40 a T-shaped head 19, which is formed on a rod 20. This rod extends through the latch housing B and in fact carries the latch C, as the latch is secured on the outer end thereof. The latch, together with the rod 20, is normally held in a projected position, such as 45 shown in Figs. 1 and 5, by means of an inner helical spring 21, but the latch is retracted against the tension of this spring when the retractor carriage is moved in the direction 50 of arrow a. It is, however, automatically projected when either spindle is released, as release of the spindle permits it to rotate back to normal position, due to the action of the springs 17 and 21.

55 The retractor carriage 14 cooperates with the push button 5 and the mechanism actuated thereby to lock the spindle D and the outer knob against rotation. This is accomplished as follows: Secured on the inner end 60 of the push button 5 is a flat rod or bar 22. Mounted on the inner end thereof are a locking plate 23 and a catch 24. The button 5 is normally held in a projected position, such as shown in Fig. 1, by means of a plunger 25 65 and a spring 26, which engages the inner end

of the bar 22, but manual depression of the button 5 will force the bar 22 and the locking plate 23 inwardly against the tension of the spring 26 and the bar 22 and plate 23 will here be locked by means of the catch 24; that is, the catch passes behind a shoulder 24a formed on the retractor carriage and the push button bar 22, together with the plate 23, is thus locked against return movement. It will further be noted that the plate 23 70 will be projected into the key-way slot 11 of the spindle D, and the spindle D, together with the outer knob 2 carried thereby, is thus locked against rotation. In other words the door cannot be opened from the outside by rotation of the knob 2, as it is locked against rotation and it will here be stated that it cannot be rotated until released. 75

Two releasing mechanisms are employed, to-wit, the mechanism actuated by rotation of the inner knob 3, and the key-actuated mechanism generally indicated at 7. Before proceeding with a detailed description of the operation of the releasing mechanism, it might be well to describe the operation of locking the lock. This is accomplished as follows: If a person is within a room and desires to lock the door, it is only necessary to push the button inwardly. 80 This, as previously described, forces the bar 22 and the locking plate 23 inwardly to a point where they are caught and secured by the shoulder 24a of the retractor carriage. This locks the outer spindle and knob against rotation and it is therefore impossible for an outsider to enter through the door as the exterior knob cannot be rotated to release the latch. It is also possible to lock the door when leaving the room. This is accomplished by depressing the button before leaving the room and then merely slamming the door closed. 85

In the lock shown in my copending application referred to, slamming of the door 100 after depression of the button would cause a release of the locking mechanism, but this is not the case with the mechanism shown in the present application. If the button 5 is depressed or pushed inwardly 105 before leaving the door and the door is slammed as the room is left, latch C will naturally become depressed; that is, it will move inwardly against the spring 21 and will compress the same, and it will again move outwardly when it reaches the opening in the keeper plate. In other words the latch can move inwardly without releasing the locking mechanism, as it does not transmit any movement to the retractor carriage. The latch bar 20 and the T-head 19 can move inwardly to assume the dotted line position shown in Fig. 5 without imparting any movement to the retractor carriage and it is for this reason that the locking mech- 110 115 120 125 130

anism cannot be released by movement of the latch C, and it is also for this reason that it is possible to lock the door and leave it closed when leaving the room.

5 The means employed for unlocking the door when returning to the room is the key-actuated mechanism indicated at 7, and the means employed for releasing the locking mechanism when inside of the room is the 10 inner knob. This releasing action and mechanism will now be described.

The mechanism actuated by the inner knob 3 is nothing more or less than the retractor carriage itself. Rotation of knob 3 15 will rotate the spindle E. This has a pair of shoulders formed on its inner end, as shown at 16 and 16a (see Fig. 5) and either one shoulder or the other will during rotation of the knob 3 and spindle E cause 20 movement of the retractor carriage in the direction of arrow a. Shoulder 24a formed on the retractor carriage will thus move outwardly or away from the catch 24, and the moment this is released bar 22, 25 locking plate 23 and button 5 are moved outwardly in the direction of arrow b by means of the action of the spring 26 and the plunger 25. This return movement of the button-actuated mechanism pulls the 30 plate 23 out of the slot or key-way 11 of the spindle D and the spindle, together with the knob 2 carried thereby, is thus released so that they will be free to rotate.

From the foregoing it will be seen that 35 the spindle D, together with the knob 2, is locked by means of depression of the button 5, and it will also be seen that they may be released by means of rotation of the spindle E and the inner knob 3, as such rotation 40 imparts movement to the retractor carriage and thereby releases the button-actuated mechanism so that it may return and interlock the spindle D and outer knob. It has also been stated that the spindle D and the 45 outer knob carried thereby may be released from the exterior by means of the key-actuated mechanism indicated at 7. To illustrate this part of the mechanism, it will again be assumed that the spindle E and 50 outer knob 2 have been locked by depression of the push button 5. A person desiring to enter from the exterior will, therefore, only have to insert a key in the opening indicated at 6. Such a key is indicated by dotted lines 55 at 30 in Fig. 2. Insertion of the key causes a rocking movement to be transmitted to a pair of rocking or pivotally mounted tumblers such as indicated at 31 and 32. These tumblers will assume a parallel position 60 when the key is completely inserted and when this parallel position is assumed, it is possible to rotate the key housing, which consists of a pair of plates 33, between which the tumblers 31 and 32 are mounted and a 65 housing 34 which carries the spring 26 and

the plunger 25. This housing also carries a projecting lug 35. This lug is best shown in Figs. 1 and 5. It is arcuate shaped as shown in Fig. 5 and lies within the shoulders 16 and 16a formed on one of the spindles. By inserting the key so that the tumblers will assume a horizontal position, it was stated that the lock housing is free to rotate. Such rotation causes the lug 35 to engage the end of the retractor carriage 14 and it thus imparts a movement thereto in the direction of arrow a in a manner similar to rotation of the inner spindle E. Such movement of the carriage releases the catch 24 and the push button, together with the bar 22 and the locking plate 23, is thus automatically retracted, thereby leaving the spindle D, together with the outer knob, free to rotate.

From the foregoing it can be seen that the spindle D and the outer knob are not only released by means of the inner knob, but also by the key-actuated mechanism carried by the outer knob. The inner knob actuates the retractor carriage to release the catch 24 and so does the key-actuated mechanism actuate the retractor carriage to release the catch 24. No detailed description has been rendered of the key-actuated mechanism as this forms the subject matter of a 95 copending application entitled "Door lock", filed May 9, 1923, Serial No. 637,638.

While a more or less specific mechanism is here disclosed, I wish it understood that the matter which I desire to cover in the present application is broadly a door lock embodying an inner and an outer knob, means for locking the outer knob against rotation, means actuated by the inner knob for releasing the outer knob, and key-actuated means also adapted to release said outer knob.

Having thus described my invention, what I claim and desire to secure by Letters Patent is—

1. In a lock of the character described, an inner and an outer knob, a lock housing in which they are journaled, means for locking the outer knob to the housing to secure the knob against rotation, key-actuated means for releasing said locking means, and means actuated by turning movement of the inner knob to release said locking means.

2. In a lock of the character described, a lock housing, a pair of knobs journaled therein, means for locking one knob to the lock housing, and against rotation with relation to the housing and leaving the other knob free to rotate, and key-actuated means for releasing the locked knob.

3. In a lock of the character described, a lock housing, a pair of knobs journaled therein, means for locking one knob to the lock housing, and against rotation with relation to the housing, and leaving the other knob free to rotate, and key-actuated means

- in the locked knob for releasing the locked knob. and also adapted to release the locking plate.
4. In a lock of the character described, a lock housing, a pair of knobs journaled therein, a button carried by one knob, means actuated by depression of the button for locking the other knob to the lock housing and against rotation with relation to the housing, and key-actuated means for releasing said button and the locking means actuated thereby. 90
5. In a lock of the character described, a lock housing, a pair of knobs journaled therein, a push button mounted in one knob, means actuated thereby for locking the opposite knob to the lock housing and against rotation with relation to the housing, a key-actuated mechanism carried by said other knob, and means actuated by said key mechanism for releasing said push button and the locking mechanism actuated thereby. 95
6. In a lock of the character described, a lock housing, an inner and an outer knob journaled therein, a push button mounted in the inner knob, a locking member actuated by the push button for locking the outer knob to the lock housing and against rotation with relation to the housing, means actuated by rotation of the inner knob for releasing said locking means to permit rotation of the outer knob, a key-actuated mechanism in the outer knob, and means actuated thereby for releasing said locking mechanism to permit rotation of the outer knob. 100
7. A lock of the character described comprising a housing, an outer and an inner spindle member journaled therein, a locking member longitudinally and manually movable in one direction within the inner spindle and adapted to engage the outer spindle and the lock housing to secure the outer spindle against rotation, and key-actuated means in the outer spindle to release said locking member and the outer spindle. 105
8. In a lock of the character described, a housing, an outer and an inner spindle member journaled therein, a bar slidably mounted in the inner spindle, a locking plate on said bar, said bar and locking plate being movable in unison, a push button secured to the bar, said push button permitting manual movement of the bar and the locking plate, interlocking means carried by the spindle and the lock housing with which the locking plate is adapted to interlock when manually moved in one direction, said plate and interlocking connections securing the outer spindle against rotation, means actuated by rotation of the inner spindle for releasing the locking plate, and key-actuated means carried by the outer spindle 110
9. In a lock of the character described, a lock housing, an inner and an outer spindle member journaled therein, a retractor carriage slidably mounted in the lock housing, a bar longitudinally movable in the inner spindle, a locking plate thereon and adapted to interlock with the lock housing and the outer spindle to secure the outer spindle against rotation, a push button on the bar to move the locking plate into interlocking position, a catch on the bar adapted to be engaged by the retracting carriage and adapted to secure the locking plate in interlocked position, means actuated by turning movement of the inner spindle for imparting movement to the retracting carriage so as to release the catch and thereby the locking plate, and a key-actuated mechanism in the outer knob whereby movement may be imparted to the retractor carriage to release the catch and the locking plate. 115
10. In a lock of the character described, a lock housing, an inner and an outer spindle member journaled therein, a retractor carriage slidably mounted in the lock housing, a bar longitudinally movable in the inner spindle, a locking plate thereon and adapted to interlock with the lock housing and the outer spindle to secure the outer spindle against rotation, a push button on the bar to move the locking plate into interlocking position, a catch on the bar adapted to be engaged by the retracting carriage and adapted to secure the locking plate in interlocking position, means for imparting movement to the retractor carriage to release the catch and the locking plate, key-actuated means carried by the outer spindle also adapted to impart movement to the retractor carriage to release the catch and the locking plate. 120
11. In a lock of the character described, a reciprocable latch, a retractor engaging the latch, an inner and an outer spindle engaging said retractor and adapted to be rotated to retract the latch, the engagement between the retractor and the latch being such that the latch may be retracted without imparting movement to the retractor, means for locking the outer spindle, key-actuated means for releasing said locking means, and means actuated by movement of the inner spindle to release said locking means. 125

WALTER R. SCHLAGE.
